CLAIM

The ornamental design for a set of supports, as shown and described.

DESCRIPTION

FIG. 1 is a front perspective view of a set of supports in use with a bench, both sides being identical;

FIG. 2 is a side view of FIG. 1, both sides being identical;

FIG. 3 is a front view of FIG. 1;

FIG. 4 is a rear side view of FIG. 1;

FIG. 5 is a top view of FIG. 1;

FIG. 6 is a side view of a set of supports of FIG. 1 in use with another bench, both sides being identical; and,

FIG. 7 is a side view of FIG. 6, both sides being identical. The broken lines showing of the bench surfaces, a support beam connecting the supports in the set of supports, the mounting feet, and the arm rests are for the purpose of illustrating environment and form no part of the claimed design. The dash-dot-dash line is for the purpose of illustrating the bounds of the claim and forms no part thereof.
